UNITED STATES PATENT OFFICE.

EDWIN ROSS MILLRING, OF ORANGE, NEW JERSEY, ASSIGNOR TO AMERICAN MACHINE & FOUNDRY COMPANY, A CORPORATION OF NEW JERSEY.

METAL-COATING APPARATUS.

Application filed April 2, 1925. Serial No. 20,220.

To all whom it may concern:

Be it known that I, EDWIN ROSS MILLRING, a citizen of the United States, residing at Orange, county of Essex, and State 5 of New Jersey, have invented a new and useful Improvement in Metal-Coating Apparatus, of which the following is a specification.

This invention relates to an improvement 10 in metal coating apparatus and it has for its main object the production of such an apparatus in which there is provided a bath of molten coating-metal, and means acting on said coating-metal to remove dross from 15 its surface at the position where coated material emerges from said bath, in order to keep the coating-metal clean at this position and to eliminate the necessity for the use of protective oil when coating certain 20 metals, and the fire hazard when oil is so used. Another object of the invention is to simplify the method of coating plate and reduce the cost of the finished product. With these and other objects not specifically 25 mentioned in view, the invention consists in certain constructions and combinations which will be hereinafter fully described and then specifically set forth in the claims hereunto appended.

30 In the accompanying drawings, which form a part of this specification and in which like characters of reference indicate the same or like parts, Fig. 1 is a plan view of an apparatus constructed in accordance 35 with the invention, and Figs. 2, 3 and 4 are respectively sectional elevations taken on the lines 2—2, 3—3 and 4—4 in Fig. 1.

In carrying the invention into effect, 40 there is provided means for supporting a bath of molten coating-metal such as lead or tin, or an alloy of lead and tin, or any other metal suitable for protective metal coating purposes, and means continuously acting on said coating-metal to remove 45 dross from its surface at the position where coated material emerges from said bath, as rapidly as said dross rises. In the best constructions contemplated, said means is removably associated with the bath so that 50 it may be bodily lifted out when it is desired to let the coating-metal cool in the kettle; said means includes two dross-drawing members partly submerged in the coating-metal on opposite sides of said position, and acting to draw the dross in opposite

directions away from said position, and means for actuating said members; said means further includes mechanism for producing separation of the dross at said position, preferably by producing two circulating currents of said coating-metal and merging them into one at said position where they break in two, and in so doing, move any particles of dross which may be at said position away therefrom in opposite 60 directions. The above mentioned devices and means may be widely varied in construction within the scope of the invention, for the particular apparatus selected to illustrate the invention is but one of many 65 possible concrete embodiments of the same. The invention, therefore, is not to be restricted to the precise details of the structure shown and described.

For the purpose of providing a bath of 70 molten coating-metal to be applied to material passed through said bath, there is provided a kettle 5 for holding the molten-coating-metal, and this kettle may be heated by means not shown but commonly employed 75 for this purpose in the art.

Removably associated with said bath is 80 means continuously acting on the molten coating-metal to remove dross from its surface at the position where coated material 85 emerges from said bath, as rapidly as said dross rises. This means includes two side plates 6 and 7, spaced apart by suitable tie-rods 8. The plate 6 is provided with angle brackets 9—9 normally resting upon 90 the upper edge of one of the walls of the kettle 5. Similarly, the plate 7 is provided with angle brackets 10—10 normally resting on the top of the opposite wall of the kettle 5. By means of the brackets 9 and 10, the various parts of the mechanism 95 now to be described are removably suspended within the kettle 5.

The particular apparatus selected to illustrate the invention is designed to be used in 100 coating sheet or plate metal, and a curved guide 11 of well known type is provided for guiding the sheet or plate through the bath of molten coating-metal. This guide is provided with the usual apertures 12 through 105 which the molten metal flows into its interior. At the delivery end of the guide 11 are two feed-rollers 13—13 fast on shafts 14—14 journaled in the plates 6 and 7. Adjacent the plate 7, the ends of the shafts 14 110

are provided with intermeshing gears 15—15 each in mesh with an idle gear 16, which in turn is in mesh with a pinion 17 fast on a shaft 18 journaled in the plates 6 and 7. Adjacent the plate 6, the shafts 18—18 carry and are driven by intermeshing gears 19—19, one of which drives a pinion 20 on a shaft 21 journaled in the plates 6 and 7, and the other of which is 10 driven by a pinion 22 fast on a shaft 23 journaled in the plates 6 and 7. The shaft 23 carries a spiral gear 24 driven by a spiral gear 25 on a short vertical shaft 26 which is journaled in bearings 27 and 28 secured to 15 the plate 6. At its upper end the shaft 26 carries a bevel gear 29 in mesh with and driven by a bevel gear 30 mounted on a short shaft 31 journaled in a bearing 32 secured to one side of the kettle 5 before referred to. The short shaft 31 also carries 20 a sprocket 33 driven by a chain 34 which also overruns a sprocket 35 mounted on a short shaft 36. The shaft 36 is rotated by means of a gear 37 driven by a pinion 38 25 on the armature shaft of an electric motor indicated at 39. When a sheet to be coated is pushed downwardly through the receiving end of the guide 11, its leading end is bent by contact with the lower curved wall 30 of the guide and directed to the feed-rollers 13—13 which seize it and pull the plate through the bath, causing it to emerge therefrom at a position above the said feed-rollers, as clearly shown by the heavy line 35 P indicating such a plate in Fig. 2.

The shafts 14—14 carrying the feed-rollers 13—13 are mounted in depending bars 40—40 and 41—41. The bars 40—40 are articulated at their lower ends at 42. 40 Similarly, the bars 41—41 are articulated at their lower ends at 43. Loosely passing through the upper ends of the bars 40—40, which rest on the plate 7, is a bolt 44 provided with a spring 45 and nut 46, by means 45 of which the bars 40—40, and consequently one end of the feed-rollers 13—13, are pressed toward each other to grip a plate coming through the guide 11. Similarly, the bars 41—41 are provided with a bolt 47, 50 spring 48 and nut 49 for causing the other end of the feed-rollers 13—13 to be pressed toward each other.

For the purpose of drawing the dross away from the position at the surface of the coating-metal where the coated plate or other material emerges from the bath, the structure selected to illustrate the invention is provided with two dross-drawing cylinders 50—50, having smooth peripheral surfaces 51—51, partly submerged in the coating-metal on opposite sides of said position and acting to draw the dross in opposite directions, as clearly shown in Fig. 2. These dross-drawing cylinders are rotated in opposite directions by the gearing hereinbe-

fore described. They act to draw the thin film of rising dross from said position to themselves and to carry this dross down into the molten metal at the submerged part of the cylinder surfaces and up again to the 70 surface of the bath behind said cylinders, where it accumulates. When the apparatus is in operation, the film of dross between the cylinders 50—50 is so thin as to be invisible to the naked eye; in fact, it probably 75 does not exist as a film at all times; but whether the rising dross is sufficient to form a continuous film or not, it is drawn away from said position by the surface tension set up by the action of the cylinders 50—50, to the surfaces of which the molten metal does not stick, the surface tension referred to being created by the friction of the cylinder surface on the molten metal. To prevent 80 particles of dross from being carried up over the tops of the cylinders 50—50 into the clean pool between them, there are provided two doctors 51—51, supported by the plates 6 and 7 and just touching the 85 peripheral surfaces of the cylinders in the 90 usual manner.

In the apparatus selected to illustrate the invention, there is further provided mechanism for producing separation of the dross at the position where coated material emerges from the bath, and this mechanism acts by producing two circulating currents of the coating-metal, merging them into one at said position, there permitting them to break up again into two currents. With this end in view, the shafts 18—18 are provided with cylinders 52—52 having fluted peripheral surfaces 53 wholly submerged in said coating-metal. These cylinders operate on opposite sides of said position and are rotated by the gearing hereinbefore described, but at a lower peripheral speed than that of the cylinders 50. The cylinders 52 produce two circulating currents of the coating-metal, as indicated by the arrows in Fig. 2, the production of these currents being aided by means of fixed baffle plates 54—54 below the cylinders 53 and baffle plates 55—55 adjacent said position. The baffle plates 54 are supported by the plates 6 and 7, while the baffle plates 55 are supported by the bars 40—40 and 41—41. As the two currents are merged into one at said position by the coaction of the rotating cylinders 52—52 and the stationary baffle plates 54 and 55, the moving metal rises above its normal level and then breaks into two currents, which in turn insures the breaking of the film of rising dross at the position where it is desirable to have perfectly clean metal, if there be any film at that position.

The action of the cylinders 50—50 alone is sufficient to remove 95% of the dross from the surface of the coating-metal lying between them, so that the metal appears to be 130

perfectly clean. But in practice it has been found that absolutely clean metal is insured by the additional use of two circulating currents of said coating-metal merged into one at said position and produced by the cylinders 52-52 and its coating baffle plates; and that when the surface of the coating-metal is thus kept absolutely clean, the necessity for the use of protective oil is entirely eliminated, and of course the fire hazard due to the use of oil is also eliminated.

What is claimed is:

1. The combination with means for supporting a bath of molten coating-metal, of means continuously removing dross from its surface at the position where coated material emerges from said bath.

2. The combination with means for supporting a bath of molten coating-metal, of means continuously removing dross from its surface at the position where coated material emerges from said bath, said means being removably associated with said bath.

3. The combination with means for supporting a bath of molten coating-metal, of means continuously acting on said coating-metal to remove dross from its surface at the position where coated material emerges from said bath, said means including two dross-drawing members partly submerged in said coating-metal on opposite sides of said position and acting to draw the dross in opposite directions, and means for actuating said members.

4. The combination with means for supporting a bath of molten coating-metal, of means acting on said coating-metal to remove dross from its surface at the position where coated material emerges from said bath, said means including two dross-drawing cylinders having smooth peripheral surfaces partly submerged in said coating-metal on opposite sides of said position, and means for oppositely rotating said cylinders.

5. The combination with means for supporting a bath of molten coating-metal, of means continuously removing dross from its surface at the position where coated material emerges from said bath, said means including mechanism for producing separation of the dross at said position.

6. The combination with means for supporting a bath of molten coating-metal, of means continuously acting on said coating-metal to remove dross from its surface at the position where coated material emerges from said bath, said means including mechanism for producing two circulating currents of said coating-metal and merging them into one at said position.

7. The combination with means for supporting a bath of molten coating-metal, of means continuously acting on said coating-metal to remove dross from its surface at the position where coated material emerges

from said bath, said means including mechanism for producing two circulating currents of said coating-metal and merging them into one at said position said mechanism including a series of baffle plates for controlling said currents.

8. The combination with means for supporting a bath of molten coating-metal, of means continuously acting on said coating-metal to remove dross from its surface at the position where coated material emerges from said bath, said means including two members wholly submerged in said coating-metal on opposite sides of said position and acting to produce two circulating currents of said coating metal and merging them into one at said position, and means for actuating said members.

9. The combination with means for supporting a bath of molten coating-metal, of means continuously acting on said coating-metal to remove dross from its surface at the position where coated material emerges from said bath, said means including two cylinders having fluted peripheral surfaces wholly submerged in said coating-metal on opposite sides of said position and acting to produce two circulating currents of said coating metal and merging them into one at said position, and means for oppositely rotating said cylinders.

10. The combination with means for supporting a bath of molten coating-metal, of means continuously acting on said coating-metal to remove dross from its surface at the position where coated material emerges from said bath, said means including two dross-drawing members partly submerged in said coating-metal on opposite sides of said position, means for actuating said members, two members wholly submerged in said coating-metal and acting to produce two circulating currents of said coating metal and merging them into one at said position, and means for oppositely rotating said cylinders.

11. The combination with means for supporting a bath of molten coating-metal, of means acting on said coating-metal to remove dross from its surface at the position where coated material emerges from said bath, said means including two dross-drawing members partly submerged in said coating-metal on opposite sides of said position, means for actuating said members, two members wholly submerged in said coating-metal and acting to produce two circulating currents of said coating metal and merging them into one at said position, means for actuating said submerged members, and a series of baffle plates coating with said submerged members to control said currents.

12. The combination with means for supporting a bath of molten coating-metal, of means acting on said coating-metal to re-

move dross from its surface at the position where coated material emerges from said bath, said means including two dross-drawing cylinders having smooth peripheral surfaces partly submerged in said coating-metal on opposite sides of said position, means for oppositely rotating said cylinders, two cylinders having fluted peripheral surfaces wholly submerged in said coating-
10 metal on opposite sides of said position and acting to produce two circulating currents of said coating-metal and merging them into one at said position, and means for oppositely rotating said submerged cylinders, the
15 peripheral speed of said dross-drawing cylinders being greater than that of said submerged cylinders.

13. The combination with means for sup-

porting a bath of molten coating-metal, of means continuously removing dross from its 20 surface at the position where coated material emerges from said bath, and means for guiding material to be coated through said bath.

14. The combination with means for sup- 25 porting a bath of molten coating-metal, of means continuously removing dross from its surface at the position where coated material emerges from said bath, and means for guid- 30 ing material to be coated through said bath including a curved guideway in said bath, and a pair of feed rollers at the end of said guideway.

In testimony whereof, I have signed my name to this specification.

EDWIN ROSS MILLRING.
